ANTIFREEZE TESTER OR SIMILAR ARTICLE

Loren P. Tichy, Mound, Minn., assignor to Thexton Manufacturing Company, Hopkins, Minn., a corporation of Minnesota

Filed Nov. 5, 1968, Ser. No. 14,326

Term of patent 14 years

Int. Cl. D10—07

U.S. Cl. D52—7

FIG. 1 is a front perspective view of an antifreeze tester, showing my new design.

FIG. 2 is a front elevational view thereof.

FIG. 3 is a rear elevational view thereof.

FIG. 4 is an elevational view of one side thereof.

FIG. 5 is an elevational view of the other side thereof.

FIG. 6 is a top plan view thereof.

FIG. 7 is a bottom plan view thereof.

FIG. 8 is a detail sectional view thereof taken approximately at 8-8 in FIG. 5.

The dominant feature of the design is the portion thereof shown in full lines.

I claim:

The ornamental design for an antifreeze tester or similar article, as shown and described.
